UNITED STATES PATENT OFFICE.

EPPA H. RYON, OF WALTHAM, MASSACHUSETTS, ASSIGNOR TO CROMPTON & KNOWLES LOOM WORKS, OF WORCESTER, MASSACHUSETTS, A CORPORATION OF MASSACHUSETTS.

PILE-CUTTER FOR LOOMS.

1,220,687.

Specification of Letters Patent. Patented Mar. 27, 1917.

Application filed July 27, 1916. Serial No. 111,732.

To all whom it may concern:

Be it known that I, EPPA H. RYON, a citizen of the United States, residing at Waltham, in the county of Middlesex and State 5 of Massachusetts, have invented a new and useful Pile-Cutter for Looms, of which the following is a specification.

This invention relates to a pile cutter for looms of a type adapted for use with a 10 grooved pile wire. It is the object of my invention to improve the construction of such pile cutters, and to render them more effective in operation.

In my present invention an important feature 15 relates to the provision of a plurality of cutting edges on a pile cutter of the type specified and also to the provision of suitable devices for successively moving said edges into operative position. Another feature 20 of my invention relates to the provision of means for sharpening said edges while they are removed from operative position. Provision is also made for moving each cutting edge to inoperative position at the end 25 of a cutting stroke, and for moving a succeeding edge into operative position at the beginning of the next cutting stroke.

My invention further relates to certain arrangements and combinations of parts which 30 will be hereinafter described and more particularly pointed out in the appended claims.

A preferred form of my invention is shown in the drawings in which—

35 Figure 1 is a top plan view of a portion of my invention;

Fig. 2 is a front elevation of the parts shown in Fig. 1;

Fig. 3 is a front elevation of certain parts 40 positioned at the opposite side of the loom;

Fig. 4 is a side elevation of the parts shown in Fig. 3, looking in the direction of the arrow 4 in said figure;

Fig. 5 is a sectional elevation taken along 45 the line 5—5 in Fig. 2;

Fig. 6 is a detail view of one end of a pile wire;

Fig. 7 is a detail plan view of the opposite 50 side end of the wire;

Fig. 8 is a plan view of the actuating connections, and

Fig. 9 is a detail sectional elevation taken on the line 9—9 in Fig. 1.

Referring to the drawings, a bar 20 is 55 shown mounted above the fabric in a loom

and supported by brackets 21 (Figs. 1 and 2) and 22 (Fig. 3) carried by the loom frame 23. The bar is adjustably secured to the brackets 21 and 22 by screws 24 and 25 passing loosely through projections on said brackets and threaded into the bar. Set screws 26 are also provided which are threaded into projections on the brackets and which engage the upper surface of the bar 20. By proper manipulation of these two sets of screws the bar may be adjusted and securely held in its vertical position.

On its front edge the bar 20 is undercut to form a guide way 20^a along which a carrier 30 is freely slideable. This carrier is pivotally connected to a link 31 which extends to the right in Fig. 1, and is secured to a reciprocating member 32 (Fig. 8) by means of a screw 33 extending through a slot 34 in the link 31. This stud and slot 75 connection permits a certain amount of lost motion between the reciprocating actuating member 32 and the carrier 30.

An arm 35 is pivoted at 36 to the carrier 30, and is yieldingly held in the position shown in Fig. 1 by a spring 37 which engages an extension 35^a of the arm 35. An adjusting screw 38 constitutes a stop which limits the movement of the arm under the influence of the spring 37.

A ratchet wheel 40 is pivotally secured to the arm 35 by a shouldered stud 41 which extends through the arm and is secured thereon by a nut 42. A disk knife 43 is secured to the ratchet wheel 40 as by a pin 44 (Fig. 5) and is provided with a plurality of cutting edges 43^a, 43^b, 43^c and 43^d. While the knife 43 is shown herein as having four cutting edges, it will be understood that this number is not essential, and that any desired number may be provided. The teeth of the ratchet wheel are positioned for engagement by a flat spring 45 (Figs. 1 and 3) secured to the top of the arm 35 by a screw 46, and adapted to retain the ratchet wheel in the position to which it is advanced by the feeding mechanism.

This feeding mechanism will now be described, and comprises a pawl 50 pivoted upon a stud 51 and yieldingly engaging the ratchet wheel 40 under the influence of a spring 52. The stud 51 is mounted upon one arm of a member 53 pivoted upon a cylindrical projection 35^b of the arm 35, and retained thereon by the nut 42, the 110

projection 35^b being concentric with the stud 41. The member 53 is provided with oppositely disposed portions 54 and 55 positioned for engagement respectively by an 5 actuating rod 56 (Fig. 3) and a bunter 57 (Fig. 2).

The actuating rod is threaded in the bracket 22 and may be adjusted longitudinally therein, being secured in adjusted position by the check nuts 58. The bunter 57 is formed as an upturned arm on a stand 59 pivoted at 60 to the fixed plate 61, and adjustable about said pivot by means of a slot 62 and bolt 63. The member 53 is also provided with a lug 53^a engaging a stop pin 64 and with a spring 65 connected to the arm 35 and normally pressing the lug 53^a against the stop pin 64.

The parts are so positioned that the rod 56 20 will engage the arm 54 as the latter approaches its left-hand limit of travel, thereby actuating the pawl and moving the ratchet wheel 40. As the ratchet is provided with two teeth for each cutting edge, the edge 25 43^a will be moved to the inoperative position shown in Fig. 2, and at the same time the succeeding edge 43^b will be advanced toward operative position. Both edges will be left, however, in the inoperative position shown 30 in Fig. 2 while the carrier is making its idle stroke to the right. As the carrier approaches its right-hand limit of travel, the arm 55 of the member 53 will be engaged by the bunter 57, and the edge 43^b will be advanced to cutting position.

The construction of the pile wire is best shown in Figs. 6 and 7, and comprises a rod 70 having a groove 71 formed therein, and having a head 72 secured to one end thereof. 40 The head is provided with a cam-like surface 72^a for a purpose to be described. At the opposite end the rod 70 is bent slightly forward so that it cannot engage and damage the reed while being inserted in the 45 warp. The operative edge 43^a of the knife 43 extends into the groove 71 of the rod 70 and co-operates therewith in cutting the pile P. As the knife completes its cutting movement the apertured head 72 is engaged 50 by a hook 32^a upon the actuating member 32, and is withdrawn thereby upon the next movement of the actuator to the right. The withdrawal of the pile wire precedes the return of the cutter to its original position, 55 owing to the lost motion provided in the connection between the link 31 and the actuator 32. A guide 73 (Figs. 1 and 9) holds the pile wire 70 in alinement while it is withdrawn by the member 53. This guide 60 is secured to the stand 59 and is adjustable thereon. The arm 35 is provided with a depending projection 35^a which is adapted to project between the rows of pile loops and to engage the most advanced of the pile wires. 65 The projection thus assists in alining the

cutting edge with the pile wire, and in retaining the parts in operative relation during the cutting stroke.

As soon as the cutter reaches the left-hand side of the loom, the cutting edges are turned to the inoperative position shown in Fig. 2, and the wire from which the loops have been cut is immediately withdrawn. The swinging arm 35 then moves backward under the pressure of the spring 37 until the projection 35^a engages the next succeeding pile wire or the loops formed thereover. This engagement continues during the advance of a new knife edge to cutting position and until the new pile wire is withdrawn after the completion of the cutting stroke. The cam surface 72^a upon the head 72 assists in guiding the cutting edge into the groove 71 of the pile wire 70.

It is found that the cutting edges in such 85 mechanism soon become dull, and I have provided new and original devices for sharpening the edges automatically without removing the same from the loom. For this purpose I secure a rod 80 to a bracket 81 90 mounted on the bar 20, and on this rod I pivotally support a pair of members 82 and 83, each provided with an abrasive surface 84. Stop pins 85—85 mounted in collars 86 limit the motion of the members 82 and 83 95 in opposite directions, in which directions said members are yieldingly pressed by springs 87 secured in collars 88 adjustable on the rod 80 to vary the tension of the springs. The stops 85 position the members 82 and 83 so that the abrasive surfaces 84 will engage the opposite faces of the cutting edge 43^c, as the edge 43^a approaches the 100 end of its operative movement.

It will thus appear that I have provided 105 a cutting mechanism co-operating with a grooved pile wire and having a plurality of cutting edges which are alternately moved to operative and inoperative positions, and that while said edges are inoperative, provision is made for sharpening them in readiness for the next operative movement.

Having thus described my invention it will be evident that changes and modifications can be made therein by those skilled 115 in the art without departing from the spirit and scope thereof as set forth in the claims, and I do not wish to be otherwise limited to the details herein disclosed, but what I claim is:—

1. A pile cutter having in combination, a rotatable disk having a plurality of separated cutting edges, means to actuate said disk intermittently to advance said edges successively to operative and inoperative 125 positions, means to retain said disk in successive positions, and a grooved pile wire co-operating with the operatively positioned cutting edge.

2. A pile cutter having in combination, 130

a knife having a plurality of cutting edges, means to move one of said edges to inoperative position at the end of the cutting stroke, and means to move a succeeding edge 5 to operative position at the beginning of the next cutting stroke.

3. A pile cutter having, in combination, a disk having a plurality of cutting edges, a ratchet secured to said disk, a pawl for said 10 ratchet, and actuating means for said pawl at each side of the loom, whereby said ratchet and disk are advanced intermittently to alternating operative and inoperative positions of the cutting edges.

15 4. In a loom, a fixed bar, a carrier slideable on said bar, an arm pivoted to said carrier, a knife having a plurality of cutting edges mounted on said arm, and means to move said knife intermittently to operative and inoperative positions of said cutting edges.

20 5. In a pile cutter, a knife having a plurality of cutting edges, a carrier on which said knife is supported, means to move said 25 knife intermittently to operative and inoperative positions of said cutting edges, and means to retain said knife in position and to prevent backward movement thereof.

30 6. A pile cutter comprising a knife having a plurality of cutting edges, means to move said knife to successive operative and inoperative positions of said edges, and means to sharpen said edges while in inoperative position.

35 7. A pile cutter comprising a knife having a plurality of cutting edges, means to move said knife to successive operative and

inoperative positions of said edges, and sharpening devices comprising abrasive surfaces mounted to yieldingly engage one 40 of said edges on both sides while in inoperative position.

8. A pile cutter comprising a knife having a plurality of cutting edges, means to move said knife to successive operative and 45 inoperative positions of said edges, and means to sharpen said edges while in inoperative position, said means comprising a supporting rod, members having abrasive surfaces mounted to swing on said rod and 50 adapted to engage said knife on opposite sides of a cutting edge, stops to limit said swinging movement, and springs to force said members toward each other.

9. A pile cutter having, in combination, 55 a carrier, a knife mounted on said carrier and having a plurality of cutting edges, means to reciprocate said carrier, and separate means positioned adjacent opposite sides of the loom and each effective to advance said knife to a succeeding position as said carrier approaches its limit of travel 60 in either direction.

10. A pile cutter having, in combination, 65 a rotatable knife having a plurality of cutting edges, and devices fixed adjacent each end of the path of travel of said knife, each effective to advance said cutter angularly through one half of the angle between 70 succeeding edges.

In testimony whereof I have hereunto affixed my signature.

EPPA H. RYON.
